US0D1110884S

(12) **United States Design Patent** (10) **Patent No.:** **US D1,110,884 S**
(45) **Date of Patent:** **** Feb. 3, 2026**

(54) **CLASP**

(71) Applicant: **ROLEX WATCH U.S.A., Inc.**, New York, NY (US)

(72) Inventor: **Davide Airoldi**, Geneva (CH)

(73) Assignee: **ROLEX WATCH U.S.A., Inc.**, New York, NY (US)

(**) Term: **15 Years**

(21) Appl. No.: **29/901,998**

(22) Filed: **Sep. 7, 2023**

(30) **Foreign Application Priority Data**

Mar. 10, 2023 (CH) 147250

(51) **LOC (15) Cl.** **11-01**

(52) **U.S. Cl.** **D11/94**
USPC **D11/94; D10/32**

(58) **Field of Classification Search**

USPC D11/200, 201, 216, 1, 3, 4, 86, 87, 93,

(57) **CLAIM**

The ornamental design for a clasp as shown and described.

DESCRIPTION

FIG. 1 is a front view of the clasp;

FIG. 2 is a rear view thereof;

FIG. 3 is right-side view thereof;

FIG. 4 is a left-side view thereof;

FIG. 5 is top view thereof;

FIG. 6 is a bottom view thereof; and,

FIG. 7 is a top perspective view thereof.

The portions of the clasp shown in broken line form no part of the claimed design. The broken line showing of a strap is for the purpose of illustrating environmental subject matter and forms no part of the claimed design.

1 Claim, 7 Drawing Sheets
